CONTROL DEVICE

William L. Stuyverson, Elkhart, Ind.

Application July 27, 1932, Serial No. 625,024

14 Claims. (Cl. 236—46)

This invention relates to stoker operation and the like, and among other objects aims to provide an improved thermostatic control device which is efficient in operation and simple and inexpensive in construction, for controlling the operation of domestic stokers.

The invention may be readily understood by reference to an illustrative construction embodying the invention and shown in the accompanying drawings.

In said drawings:

Fig. 1 is an elevation, somewhat diagrammatic in character, showing the relation of the control device to one form of domestic stoker;
15 Fig. 2 is a transverse vertical section of the control device taken on the plane 2—2 of Fig. 4 showing the controlling element;

Fig. 3 is a plan view of the device taken just below the cover of its enclosing housing;

20 Fig. 4 is a longitudinal section taken on the plane 4—4 of Fig. 2; and

Figs. 5 and 6 are detail views illustrating the operation of the control mechanism.

The illustrative control device is here shown applied to a rotary domestic stoker of the type illustrated in my copending application, Serial No. 584,503, although it is obvious that use of the control device is not limited to stokers of this type. The aforesaid rotary stoker 10 feeds coal periodically in small charges through the feeding tube 11 into the furnace 12 and allows it to drop upon the fire. The amount of each charge is made small enough so that any smoke which may be generated by contact of the fuel with the hot fire will be substantially consumed and will not pass up the stack. Delivery of periodic charges of fuel is effected by placing one or more baffles inside the rotary coal hopper 13 which, upon rotation of the hopper, cause a quantity of fuel to be dropped into the open upper side of tube 11 through which it is conveyed by a screw conveyor or the like into the fire-box. The hopper is rotated by a motor 14 geared with the gear ring 15 on the hopper. The intensity of the fire may be varied by varying the frequency with which the hopper is operated.

The illustrative control device is adapted to actuate the stoker at relatively infrequent intervals to maintain a minimum fire and also to actuate it periodically at shorter intervals depending upon the temperature demand. The actuating element is here represented by a rotating shaft 16 having a plurality of control fingers 17 adapted in the event of temperature demand 45 each to actuate the stoker once for each revolution of shaft 16. The number of fingers upon the shaft depends somewhat upon the speed of rotation of the shaft. In the present instance the shaft is driven slowly and makes one revolution in about one hour's time. A spring clock mechanism or electric clock for that reason may advantageously be used to rotate shaft 16, although it is obvious that any other driving mechanism would be equally satisfactory. The shaft driving mechanism is indicated at 18 and is located at one end of the enclosure 19 surrounding the control apparatus.

The control mechanism is constructed and arranged so that one of the fingers, that here marked 20, actuates the stoker mechanism once each revolution regardless of temperature demand, and thus functions as the means for maintaining a minimum fire in the furnace. For ordinary domestic use, the finger 20 actuates the stoker for about five minutes once each hour, 20 during which small periodic charges of fuel aggregating about five pounds are fed into the fire-box. The mechanism is also constructed and arranged so that the other fingers 17 operate selectively depending upon the temperature demand.

The fingers 17 and 20 are arranged to close an electric contact when they arrive at a given point in order to operate the stoker, said electric contact being here shown in the form of a rockable mercury switch 21 whose terminals 22 are connected by a quantity of mercury 23 inside the tube when the latter is tilted to cause the mercury to flow toward the contacts. Wires 24 are connected through a source 25 of the electric current to motor 14. The switch is shown pivoted at 26 to the structure of the driving mechanism 18 and is provided with an operating lever 26 projecting, in this case downwardly, into the path of the operating fingers. The switch is 40 rocked to close the circuit when the finger 20 for example engages lever 26 and as soon as the bottom of the mercury tube is tilted just beyond level position so that the mercury flows toward the terminals 22 where it remains so long as the 45 tube is held tilted by finger 20. To control duration of the period when the switch is closed, the end of lever 26 is provided with a cam surface 27 laterally projecting into the path of finger 20. The under face of the cam is here shown 50 with a longitudinal convex curvature corresponding somewhat to that of the arc traversed by the ends of fingers and arranged (when the switch is in closed position) so that its outer end 28 is somewhat closer to the center of shaft 16 55

than its front end 29. This insures that the switch will be held in closed position from the time it is sufficiently tilted by engagement of the finger with the projecting edge 29 until the finger traverses the entire length of the cam surface 27. In the present instance, this period is in the neighborhood of five minutes where the shaft rotates about one revolution per hour. This period may be varied by varying the length of the cam surface 27 and for that purpose one portion 30 of the cam surface may be made longitudinally slidable relative to the other portion 31. For purposes of adjustment the flange 32 of the movable section of the cam is slotted and held in adjusted position relative to the other portion 31 by means of a bolt 33 or the like.

When a finger clears the outer end of cam 28 the switch is released and tilts in the opposite direction to open the circuit. A pin 35 limits the backward tilting of the switch.

To secure the selective action of the control fingers 17 in response to temperature demands, the mechanism is arranged so that they may be made to engage or clear the lever 26 depending upon whether or not additional fuel is required. As here shown (see Fig. 4) fingers 17 are bent outwardly at their extremities so that normally they clear the extremity of lever 26 and the cam 27. They are actuated to engage cam 27 in response to temperature demands by a thermostatically controlled guide bar 36 whose end 37 has a tapered or cam like outline adapted to be engaged by the extremities of fingers 17 and to be cammed or guided inwardly (see Fig. 4) into alignment with cam 27. The guide bar 36 is in this instance controlled by a bi-metallic thermostatic element 38 supported on a rod 39 and to one end of which the guide bar is connected. The other extremity 40 of the thermostatic element 38 is connected to a pivoted adjusting lever 41 which may be rocked back and forth through a limited arc to vary the temperature at which the guide bar acts. The lever has an operating finger passing through a slot in the housing adjacent which is a temperature scale by which the necessary adjustment of the thermostat may be regulated by moving the finger to the right or left.

When the room temperature (in which the thermostat is located) exceeds the desired maximum, the thermostat raises bar 36 upwardly beyond the end of fingers 17 which therefore do not actuate the stoker. When the temperature reaches the predetermined minimum, the bar 36 is lowered until it comes into the path of fingers 17 which are then guided over into alignment with cam 27. If a finger 17 has once been placed in operative connection with cam 27 it is held against springing out by channeling the under face of the cam to provide a downwardly extending flange 42 which constrains fingers 17 to travel along cam 27 until they clear its end 28.

A stop in the form of an inwardly projecting bar 43 is provided to prevent excessive lowering of the guide bar 36 to a point beyond operative engagement with fingers 17, in the event of a sudden chilling of the thermostat by an open door or window. Thus for all temperatures below the minimum at which the device operates, the guide bar 36 is always in operative relation to the fingers 17.

The normal minimum duration of the switch closure may be further reduced if it seems desirable by tilting the entire control device in a clockwise direction (see Fig. 2). This has the effect of requiring additional travel of the fin-

gers 17 or 28 (after they are in engagement with cam 27) before the switch tube 21 is tilted beyond level position to cause the mercury to flow toward the contact end of the tube. Tilting of the device may be effected in any appropriate manner such as by screw 44 adapted when driven down to elevate one edge and thus rotate the control device in a clockwise direction.

If shaft 16 be driven by clock spring motor, switch 24 may advantageously be counter-weighted to avoid the possibility that the motor may run down when the switch is closed and thus indefinitely continue the operation of the stoker. The counter-weight 45 increases the resistance to rocking of the switch to closed position so that unless the spring motor has enough residual energy to continue in operation long enough to carry a finger beyond the cam (and thereby allow the switch to open), it will not be powerful enough to tilt the switch to close it. In the latter case the motor will be stopped when it encounters the forward edge 29 of the cam, since the greatest force must be initially exerted to start the rocking movement of the switch under the resistance of both the mercury and the counter-weight.

Obviously the invention is not limited to the details of the illustrative construction since these may be variously modified. Moreover it is not indispensable that all features of the invention be used conjointly since various features may be used to advantage in different combinations and sub-combinations.

Having described my invention, I claim:

1. In apparatus of the character described the combination comprising a stoker adapted to feed periodic charges of fuel, a motor for operating said stoker, a motor switch, a rotating control device having switch actuating members projecting therefrom for periodically closing said switch upon rotation of said device, and means for rendering a member inoperative to close the switch.

2. In apparatus of the character described the combination comprising a stoker adapted to feed periodic charges of fuel, a motor for operating said stoker, a motor switch, a rotating control device having switch actuating members projecting therefrom and adapted periodically to actuate said switch, and thermostatically controlled means for moving said members into operative relation to said switch.

3. Stoker control apparatus of the character described comprising in combination an electric switch, a continuously rotating shaft having a plurality of switch operating fingers projecting therefrom and arranged so as normally to clear said switch upon rotation of said shaft, and a thermostatically actuated member adapted at low temperature to move said fingers into operative engagement with said switch.

4. Stoker control apparatus of the character described comprising in combination an electric switch, a continuously rotating shaft having a plurality of switch operating fingers projecting therefrom and adapted periodically to engage and close said switch for limiting periods of time, and a temperature controlled device for rendering a finger inoperative when minimum temperatures are exceeded.

5. Stoker control apparatus of the character described comprising in combination an electric switch, a continuously rotating shaft having a plurality of switch operating fingers projecting therefrom, certain of said fingers being arranged so as normally to clear said switch, and a tem-

perature controlled device for moving a finger into operative relation to said switch at low temperature.

6. Stoker control apparatus of the character described comprising in combination an electric switch having a projecting cam, and rotating switch fingers adapted periodically to engage said cam to close the circuit during the period of contact with said cam, one or more of said fingers being displaceable to effect cam engagement.

7. Stoker control apparatus of the character described comprising in combination an electric switch having a projecting cam adjustable in length, and rotating switch fingers adapted periodically to engage said cam to close the circuit during the period of contact with said cam, said cam being adjustable to vary the duration of contact therewith.

8. Stoker control apparatus of the character described comprising in combination an electric switch, a continuously rotating shaft having a plurality of switch operating fingers projecting therefrom and arranged so as normally to clear said switch upon rotation of said shaft, a thermostatically actuated member adapted at low temperature to move said fingers into operative engagement with said switch, and another finger on said shaft arranged to actuate said switch independently of said thermostatically actuated member.

9. Stoker control apparatus of the character described comprising in combination an electric switch having a rocking cam adapted to be rocked to close the electric circuit, a plurality of moving fingers adapted periodically to engage said cam to close the circuit and means for varying the frequency of engagement of said fingers with said cam, by displacing one or more of said fingers.

10. Stoker control apparatus of the character described comprising in combination an electric switch having a rocking operating cam with a channeled face, a plurality of moving fingers for engaging said cam to close the switch, said

fingers being arranged so as normally to clear said cam, and means for engaging said fingers to cause the same to engage the channel of said cam, said channel serving to prevent premature disengagement from said cam.

11. Stoker control apparatus of the character described comprising in combination an electric switch having a rocking operating cam with a channeled face, a shaft having a plurality of spring fingers projecting therefrom and normally arranged to clear said cam, and a thermostatically controlled guide for engaging said finger to move the same into register with the channel of said cam.

12. Stoker control apparatus of the character described comprising in combination an electric switch having a rocking cam adapted to be rocked to close the electric circuit, a plurality of moving fingers adapted periodically to engage said cam to close the circuit, and means for varying the frequency of engagement of said fingers with said cam, said means including thermostatically actuated means for displacing one or more of said fingers.

13. Stoker control apparatus of the character described comprising in combination an electric switch having a movable cam adapted to be moved to close the electric circuit, a plurality of moving fingers adapted periodically to engage said cam to close the circuit, and means for varying the frequency of engagement of said fingers with said cam, said means including temperature actuated mechanical means for displacing one or more of said fingers.

14. Control apparatus of the character described, comprising an electric switch, a continuously rotating shaft having a plurality of equally spaced switch actuating members, one of said members set to actuate said switch each revolution of said shaft, and temperature controlled means adapted to selectively operate the remaining member to actuate said switch as temperature setting demands.
